UNITED STATES PATENT OFFICE

THOMAS A. GLENDON, JR., OF NEW YORK, N. Y., ASSIGNOR TO HELBURN THOMPSON CO., OF SALEM, MASSACHUSETTS, A CORPORATION OF MASSACHUSETTS

DESIGN FOR LEATHER OR SIMILAR ARTICLE

Application filed April 15, 1929. Serial No. 30,913. Term of patent 7 years.

To all whom it may concern:

Be it known that I, THOMAS A. GLENDON, Jr., a citizen of the United States, and resident of New York, in the county of New York and State of New York, have invented a new, original, and ornamental Design for Leather or Similar Article, of which the following is a specification.

In the accompanying drawing:—

The figure is a surface view of a piece of leather or similar article showing my new design and the area within the intersecting indicating lines constitutes one complete unit of the design, the other portion being repeat units arranged around the complete unit.

The dominant feature of the design consists in the provision in each block of a plurality of substantially circular figures which are of different sizes and arranged substantially so that the large circular figures are positioned in one corner of the block and gradually the smaller circular figures are arranged in diminishing order so that the smallest is positioned in the diagonally opposite corner, and in the arrangement of the blocks in adjacent vertical and horizontal rows so that alternate blocks in alternate horizontal rows have their large circular figures at the top right side and the other blocks of said alternate horizontal rows have their large circular figures on the bottom right side, and in the other of said horizontal rows alternate blocks have their large circular figures on the top left side and the other blocks of said other horizontal rows have their large circular figures on the bottom left side, and adjacent horizontal rows are relative to each other so that the large circular figures on the dividing line in each are diagonal to each other.

I claim:—

The ornamental design for leather or similar article, as shown and described.

Signed at New York, in the county of New York and State of New York, this 9th day of April, A. D. 1929.
